LOUIS GINGRAS, OF LOWELL, MASSACHUSETTS, ASSIGNOR OF ONE-HALF TO A. PIERRE GINGRAS, OF LOWELL, MASSACHUSETTS.

POCKET TOOL-HOLDING DEVICE.

1,163,526.

Specification of Letters Patent.

Patented Dec. 7, 1915.

Application filed May 19, 1915. Serial No. 29,197.

To all whom it may concern:

Be it known that I, LOUIS GINGRAS, a citizen of the United States, residing at Lowell, in the county of Middlesex and State of Massachusetts, have invented certain new and useful Improvements in Pocket Tool-Holding Devices, of which the following is a specification.

This invention relates to pockets and to tool retaining devices which may be inserted therein so as to grip a tool which may be placed in the pocket in such a manner as to prevent it from easily slipping out therefrom.

15 The device is so constructed that it can be readily inserted in any pocket within reasonable limits of size and can be readily detached therefrom. When in place, it cannot be shaken out of the pocket or out of place. When in place, it not only is so arranged as to readily receive a tool but it helps to hold the mouth of the pocket open so that the tool may be readily slipped thereinto.

25 It is especially adaptable for pockets in overalls in which carpenters' rules of a well known type are usually carried.

The invention consists generally in the combination for a pocket, of removable pocket gripping means, and tool gripping means fixed thereto.

30 More specifically, it comprises the combination of a substantially U shaped unitary clip member of narrow spring metal, the two substantially parallel arms of which are spring pressed away from each other and carry on their inward sides tool gripping parts or fingers spring pressed toward each other so as to yieldably engage opposite sides 40 of a tool or the like.

In the drawings, Figure 1 is a front elevation of the preferred form of my device when removed from the pocket. Fig. 2 is a front elevation of my device in place in a 45 pocket with a carpenter's rule in place therein. Fig. 3 is a top view of Fig. 2. Fig. 4 is a detail showing how this device can be made of a single strip of metal. Fig. 5 is a view from the right of Fig. 4 looking in the 50 direction of the arrow. Fig. 6 is a front elevation of a modification of the device in place in a pocket, shown by the dotted lines, with a pair of pliers in place therein. Fig. 7 is a detail front elevation and Fig. 8 an 55 elevation from the right of Fig. 7 showing

another type of tool gripping member. Fig. 9 is a front elevation of another modification made of a single piece of spring metal, Fig. 9 showing it by itself and Fig. 10 in place in a pocket shown by the dotted lines.

Similar letters and numbers refer to similar parts.

The preferred form of my device shown in Figs. 1 and 2 has its pocket gripping member formed of a single strip of narrow spring metal A, B, C bent in substantially a U shape having a bottom B and side arms A and C which preferably slope away from each other as shown. Sides A and C are 70 bent outwardly at their ends 10 and 11 to form outwardly projecting claws or teeth which are preferably not very sharp.

The tool gripping parts are fingers 12 and 13 which are preferably made of spring metal each attached at one end by rivets, solder or otherwise near the top on the inside of an opposite arm A or C. These spring fingers preferably curve inwardly toward each other with a generous curve and then 80 extend downward sloping toward each other as shown.

H represents the cloth of a garment and K represents a pocket having a bottom edge 20 and opposite lengthwise edges 21 85 and 22.

24 is a carpenter's rule of a well known type.

When my device is taken between the fingers and thumb and the side arms A and C are squeezed together, it can be readily inserted in the pocket K, and when the arms are released as shown in Fig. 2, the claws 10 and 11 will grip the cloth at points adjoining the opposite lengthwise edges of the 95 pocket and will hold the device in place until the arms A and C are again pressed together. If a tool such as rule 24 is inserted into the pocket, it will be guided by fingers 12 and 13 so that it must be pressed down between them forcing them somewhat apart and when once in place, the pressure of these fingers thereon will hold it in place and prevent it from slipping out.

The arms A and C may be made wide 105 enough so as to distend the pocket and keep its front wall away from its back wall, whereby a tool may be the more readily inserted therein. This is shown in Fig. 3.

In Fig. 6, a pocket is shown in dotted lines 110

and a somewhat different construction is shown wherein the sides A and C and bottom B together with claws 10 and 11 are the same, but the tool gripping parts 14 and 15 5 are fixed to A and C each at a point well down thereon and the upper ends of these fingers instead of the lower ends are free to be pushed aside. In such case, it is well 10 to bend such upper ends 16 and 17 outwardly to more readily receive the tool, such for instance as the pliers 25. Instead of allowing the tool gripping parts to have a free end at the top or bottom, I may use a bow shaped part such as 30 shown in Figs. 7 and 8 which 15 has a slot 32 or 33 at each end through which passes a headed stud 34 or 35 fixed to the inside of a part A or C. The slots permit this spring tool holding part to give when a tool is inserted or withdrawn.

20 In Figs. 9 and 10, I show another modification wherein the whole device is made of one strip of spring metal. This is bent in a U shape at the bottom 40, thence upward at 41 and 42, thence outward at 43 and 44 and 25 at the end still more outwardly to form claws 45 and 46.

As shown in Fig. 10, when this device is in place, the angle between the parts 41 and 43 and between 42 and 44 will engage a tool 30 such as rule 24, while the whole device will tend to press outwardly the claws 45 and 46.

The construction shown in Figs. 1, 2 and 3 may be modified as shown in Figs. 4 and 5 by being made entirely of one strip of sheet 35 metal which extends upward and outward forming the pocket gripping members, such as 50, which are then bent sharply back and inward as shown at 51, while a claw or tooth 52 is stamped outwardly from the metal as 40 shown. By this construction, the use of rivets or solder between the tool gripping parts and the pocket gripping member is avoided.

It is desirable that the tool gripping parts

at their tops, which ever form is used, should curve well up and toward each other so that 45 when they are distorted as the tool is forced between them, they will grip it near its upper end instead of near its lower end, as it is thereby held more firmly.

I prefer to use a flat strip of metal for the 50 pocket gripping members as the pocket is thereby kept open allowing a tool to be more readily inserted, but it is manifest that strips of round or oval metal might be used in place thereof. I prefer the claws or teeth 55 on the outside at the ends of the pocket gripping arms but they may be anywhere on the exterior sides thereof.

I claim:

1. In a device of the character described, 60 a substantially U-shaped unitary clip member formed of narrow spring metal, the opposite arms thereof adjacent the top, having outwardly projecting claws to engage the opposite lengthwise edges of a pocket, and 65 also having inwardly projecting parts adapted to yieldably engage opposite sides of a tool or the like.

2. In a device of the character described, 70 a substantially U-shaped unitary clip member of narrow spring metal having outwardly projecting claws at its upper ends to engage the opposite lengthwise edges of a pocket, and two oppositely disposed inwardly projecting spring fingers each projecting and curving inwardly and downwardly from its fixed end toward the other 75 so that they are adapted to engage the opposite sides of a tool.

In testimony whereof I hereto affix my signature in presence of two witnesses.

LOUIS GINGRAS.
